UNITED STATES PATENT OFFICE.

EUGENE L. BARNES, OF BUFFALO, NEW YORK, ASSIGNOR TO THE BARBER ASPHALT COMPANY, OF PHILADELPHIA, PENNSYLVANIA, A CORPORATION OF WEST VIRGINIA.

REFRIGERATING APPARATUS.

Application filed May 4, 1927. Serial No. 188,692.

My invention relates to refrigerating apparatus, and more particularly to apparatus for developing and utilizing the refrigerating effect from the working substance or refrigerant,—e. g., the “evaporator and cooler” of systems operating on the compression-condensation-vaporization cycle. I aim to provide a simple, convenient, compact, and efficient vaporizing and cooling device. In suitable forms of embodiment, such as herein-after described, the invention lends itself to easy and expeditious manufacture in a variety of sizes, by assembly of standard parts that can be easily and inexpensively made out of sheet metal by die-stamping processes. The invention is particularly adapted and advantageous for “flooded” systems, as they are termed, in which a body of liquid in the low pressure side of the system gradually vaporizes or “boils” as it absorbs heat from the region or article that it is desired to refrigerate. I have here shown and described embodiments of the invention suitable for use in a refrigerating box or compartment such as the ice chamber of an ordinary household refrigerator.

In the drawings, Fig. I shows a side elevation of a device or apparatus conveniently embodying the invention.

Fig. II shows a front elevation of the same apparatus.

Fig. III shows a vertical longitudinal section through the apparatus, taken as indicated by the line III—III in Fig. II.

Fig. IV shows a vertical transverse section through the apparatus, taken as indicated by the line IV—IV in Fig. I.

Fig. V is an edge view of one of the upright vaporizing sections shown in Figs. I to IV.

Figs. VI and VII are edge views of sheet metal halves which may be united to form such a section.

Fig. VIII shows a side elevation of a device similar to that shown in Figs. I to VII, but of different proportions.

Fig. IX shows a front elevation of the device shown in Fig. VIII.

Fig. X is an edge view of one of the vaporizing sections shown in Figs. VIII and IX.

Fig. XI is a front elevation of a device larger than that shown in Figs. VIII and IX, involving a different arrangement of the vaporizing sections of Figs. VIII and IX.

Fig. XII is a plan view of the device shown in Fig. XI.

As shown in Figs. I to VII, the apparatus comprises a series of upright transverse vaporizing sections 15, together with a common longitudinal refrigerant chamber or drum 16, and one or more longitudinal cooling chambers or compartments for material to be refrigerated. In the present instance, there are two such cooling compartments 17 and 18, the former an approximately square chamber adapted for keeping food, freezing deserts, or the like, and the latter a wide, shallow, horizontal chamber adapted to contain one or more trays for freezing ice cubes or the like. As shown in Figs. II and IV, the refrigerant chamber 16 is located at the upper righthand corners of the sections 15, and the cooling chamber 17 at their upper lefthand corners. The cooling chamber 18 is located at or in the lower portions of the sections 15, directly beneath the refrigerant chamber 16 and the cooling chamber 17.

As shown in Figs. I to IV, the refrigerant chamber 15 has the character of a cylindrical drum or large tube extending from one section 15 to the next at or in suitable openings in the walls of said sections, and itself opening into or communicating with their interiors. In the present instance, the tube or drum lengths between adjacent sections 15 are not separate, but consist of one single long tube,—

extending unbroken through all the sections 15, though pierced with a plurality of holes or openings 19, 20 in its lower and upper portions, so located and of such size and number as to afford ample passage for liquid and/or vaporous refrigerant from drum 16 to sections 15 and vice versa. Besides the openings for the refrigerant chamber 16, the sections 15 have openings through which the cooling chambers 17, 18 extend; and thus the sections 15 are of a grid-like character. How-

ever, the openings for the cooling chambers 17, 18 have their edges closed. As shown in Figs. I and III, the rear end of the drum 16 is closed by a cylindrically flanged cover 21 fitting and permanently secured therein, while its front end is provided with a flange 22 for the attachment of a removable cover plate 23, which may be secured by means of bolts 24. As shown in Fig. II, the cover 23 is provided with tapped openings 25 for such

connections to the rest of the refrigerating system as may be desired, including inlet and outlet for liquid and vaporous refrigerant.

The vaporizing sections 15 are shown as of 5 thin, flat form, and are preferably made of sheet metal. As shown in Figs. VI and VII, each section 15 consists of "right" and "left" dished sheet metal halves 26, 27, which may readily be formed by a die-stamping operation. When these halves are brought together, as shown in Fig. V, the lateral edge flanges of the half 26 fit within those of the half 27, so that the flanges may readily be secured together fluid tight by soldering, brazing, or welding. The lateral flanges 28, 29 around the openings for the cooling chambers 17, 18 interfit and are secured together in a similar manner. The lateral flanges 30, 31 around the openings for the refrigerant drum 16 are turned outward or reversed (as compared with the flanges 28, 29), so that they may readily be secured to the exterior of the drum 16 by soldering, brazing, or welding after the sections have been put in place on the drum, as shown in Fig. III.

The cooling chambers 17 and 18 may be inserted in the openings in the sections 15 after the latter have been properly mounted and secured on the drum 16, and may be secured to said sections 15 in any suitable manner (as by soldering, brazing or welding), so as to assist in bracing said sections relative to one another and to the drum 16,—thus protecting the fluid tight joints of said sections 35 with the drum 16 against injury from accidental blows or impacts to which said sections 15 may be subjected.

It will readily be seen from Figs. I, III, and IV, especially, that the vaporizing sections 40 afford free passage for the liquid refrigerant all around the cooling chambers 17 and 18, and are in intimate thermo-conductive contact with them all the way around. Thus the absorption of heat from the chambers 17 45 and 18 is most effective. Also, the liquid and vapor circulate freely around the drum 16, and have free passage out of and into it through the openings 19, 20. The sections 15 have ample heat absorbing surfaces freely 50 exposed to the atmosphere of the compartment in which the device is located,—with ample room for circulation of the air around the sections and around the drum 16. The air thus cooled by the sections 15 and the drum 55 16 also comes freely in contact with the chambers 17 and 18 intermediate the sections 15.

It will be apparent that by lengthening the chambers 16, 17 and 18,—or by spacing the vaporizing sections 16 more closely,—the exposed surface and cooling capacity of the device can be increased to any extent desired.

Figs. VIII, IX, and X illustrate an apparatus similar to that of Figs. I to VII, but larger. In the present instance, it not only 60 has half a dozen vaporizing sections 15^a as

against four sections 15 in Figs. I to VII, but also has four of the thin, flat horizontal cooling chambers 18^a as against one such cooling chamber 18 in Fig. VIII. The only difference that this requires in the parts employed is an increase in the height of the sections 15^a in correspondence with the greater number of cooling chambers 18^a, and a lengthening of the parts 16, 17, 18 to correspond to the greater number of sections 15^a. 70 75

Figs. XI and XII illustrate the construction of an apparatus of yet larger size and cooling capacity out of grid sections 15^a such as shown in Figs. VIII, IX, and X. As here shown, the individual sections 15^a are 80 exactly like those of Figs. VIII, IX, and X; but instead of being all arranged with their openings for the refrigerant drum 16 at the right, as in Fig. IX, they are arranged with these drum openings at right and left alternately, so that the alternate sections 15^a project to opposite sides of the drum 16, and the sections appear staggered in plan (Fig. XII). Also, the sections 15^a are spaced more closely together along the drum 16 in Fig. 90 95 XII than in Fig. VIII. As shown in Figs. XI and XII, there are ten of the alternately reversed vaporizing sections 15^a, spaced more closely than in Figs. I, III, and VIII; and there are food chambers 17, 17 at both sides 100 of the drum 16, extending through the openings in the correspondingly projecting sections 15^a. In this instance, there is only a single vertical central "stack" of chambers 18^b,—not so wide as those of Figs. I to IX,— 105 extending through the overlapping ends of the corresponding openings in the staggered arranged sections 15^a (Fig. XI).

Having thus described my invention, I claim:

1. A refrigerating apparatus of the character described comprising a series of upright transverse hollow vaporizing grid sections, with a longitudinal refrigerant duct extending through openings in the sections 110 and pierced with openings into their interiors, the duct being in fluid tight relation with the openings in the sections, and a longitudinal cooling chamber also through openings in said sections. 115

2. A refrigerating apparatus of the character described comprising a series of upright transverse hollow sheet metal vaporizing grid sections with outward-flanged openings in their upper portions, a longitudinal refrigerant drum in said openings secured fluid tight to their flanges and pierced with openings into the interiors of said sections, and a longitudinal cooling chamber mounted in other openings in said sections. 120 125

3. A refrigerating apparatus of the character described comprising a series of vaporizing grid sections and a refrigerant duct extending through and communicating in a fluid tight manner with the sections, the lat- 130

ter being staggered to right and left alternately with reference to said chamber.

4. A refrigerating apparatus of the character described comprising a series of upright transverse vaporizing sections, a common refrigerant duct extending through and communicating in a fluid tight manner with said sections, and a longitudinal cooling chamber also extending through said sections, and having its walls conductively connected to said sections.

5. A refrigerating apparatus of the char-

acter described comprising a series of upright transverse hollow vaporizing grid sections with a central longitudinal refrigerant chamber in upper corner openings formed in the right and left sides of the sections in alternation, and longitudinal cooling compartments mounted in other openings in said sections.

In testimony whereof, I have hereunto signed my name at Buffalo, N. Y., this 28th day of April, 1927.

EUGENE L. BARNES
